UNITED STATES PATENT OFFICE.

GEORGE GILL, OF TAUNTON, MASSACHUSETTS, ASSIGNOR TO REED AND BARTON, OF SAME PLACE.

DESIGN FOR A CARD-RECEIVER.

Specification forming part of Design No **6,378**, dated February 4, 1873.

To all whom it may concern:

Be it known that I, GEORGE GILL, of Taunton, in the county of Bristol and State of Massachusetts, have invented a new and original Design for a Card-Receiver; and I do hereby declare the following to be a full, clear, and exact description of the same, reference being had to the accompanying drawing forming a part of this specification.

The invention consists in a new and ornamental design for card-receiver and analogous articles; also for the configuration of the body and stand, as hereinafter described.

The drawing is a perspective view of card-receiver.

A represents the body of a card-receiver formed of three leaves, *a a a*, interlocking each other, and with their concave sides upward to conveniently hold the cards. B B B are three bows or circular rods, with their points of greatest convexity brought into contact, or

nearly so, between base and body, while one end of each rests upon and is affixed to one of the arms of the tripod base C. At the point of junction of the bows B may be applied some ornamentation, as shown in the drawing.

Having thus described my invention, what I claim as new, and desire to secure by Letters Patent, is—

1. As a new design for the body of a card-receiver, the interlocked and upwardly-convex leaves *a a a*, as shown and described.

2. As a new design for the stand of card-receivers, the bows B B B, arranged between base and body, as shown and described.

3. The design for a card-receiver, having the body and stand formed as shown and described.

GEORGE GILL.
